CLAIM

The ornamental design for an orthosis component, as shown and described.

DESCRIPTION

FIG. 1 is a rear perspective view of an orthosis component showing our design.

FIG. 2 is a front perspective view of the orthosis component of FIG. 1.

FIG. 3 is a front elevational view of the orthosis component of FIG. 1.

FIG. 4 is a rear elevational view of the orthosis component of FIG. 1.

FIG. 5 is a first side elevational view of the orthosis component of FIG. 1.

FIG. 6 is a second side elevational view of the orthosis component of FIG. 1.

FIG. 7 is a top plan view of the orthosis component of FIG. 1; and,

FIG. 8 is a bottom plan view of the orthosis component of FIG. 1.

The broken lines illustrate portions of the orthosis component which form no part of the claimed design.
